LOOPER THROWOUT MECHANISM

Andrew B. Clayton, Elizabeth, N. J., assignor to
The Singer Manufacturing Company, Eliza-
beth, N. J., a corporation of New Jersey

Application January 1, 1945, Serial No. 570,925

13 Claims.

(Cl. 112—200)

This invention relates to chain stitch sewing machines and more particularly to a control for the thread-carrying looper mechanism of such machines.

The primary object of the invention is to provide an improved looper throw-out for retracting the looper from a normal, operating position adjacent the needle to a more convenient threading position, the mechanism being arranged for ready manipulation by the operator and without interference with the normal use of the machine.

With the above and other objects in view, as will hereinafter appear, the invention comprises the devices, combinations and arrangements of parts hereinafter set forth and illustrated in the accompanying drawings of a preferred embodiment of the invention, from which the several features of the invention and the advantages attained thereby will be readily understood by those skilled in the art.

In the accompanying drawings:

Fig. 1 is a vertical, longitudinal section of a portion of a sewing machine embodying the invention;

Fig. 2 is a cross-section approximately on the line 2—2 of Fig. 1;

Fig. 3 is a front elevational view showing the control handle and associated parts in different positions of adjustment;

Fig. 4 is a vertical section on the line 4—4 of Fig. 2;

Figs. 5 and 6 are detail views of parts of the mechanism;

Fig. 7 is a vertical section on the line 7—7 of Fig. 1;

Fig. 8 is a horizontal section on the line 8—8 of Fig. 2; and

Fig. 9 is a cross-section on the line 9—9 of Fig. 8.

For purposes of illustration the invention is applied to a sewing machine of the general construction disclosed in United States Patent No. 2,345,327, Mar. 28, 1944, only so much of the machine being shown and described herein as is necessary to an understanding of the invention.

The machine comprises a bed or work-supporting plate, generally designated 1, set into a table top 2. Immediately below the bed 1 and suitably supported from the table is a stationary base or housing 3 which encloses the under-bed mechanism below described. At its rear (see Fig. 2) the machine bed 1 is connected to the table by hinge elements 4, 5, so that the bed can be bodily raised to expose and afford ready access to the mechanism mounted on the underside of the bed.

In general, such mechanism comprises a rotary drive-shaft 6 incorporating a crank 7 and an eccentric 8 by which, respectively, the requisite endwise reciprocating and sidewise or laterally vibrating movements are imparted to a looper 9 mounted on a looper-carrier 10. The endwise reciprocatory movements of the looper are effected through the medium of a pitman 11, rocker arms 12 and 13 journaled on a stud 14, and a link 15 connecting rocker arm 13 with the looper-carrier 10. The sidewise or laterally vibrating movements of the looper are effected through the medium of an eccentric-actuated fork 16 and rock-shaft 17, the latter journaled in bushings 18, 19 fitted within a bearing support 20 forming part of the bracket 21 depending from the underside of the bed 1. The rock-shaft 17 in turn supports the looper-carrier in the manner to be described.

On the end of the rock-shaft 17 remote from the fork 16 is a tubular cross-head 22 (Figs. 4, 5 and 7) and journaled in the cross-head is a rocker member 23 having an eccentric bore 24 and a depending arm 25. As shown in detail in Fig. 4, the rocker member 23 is normally held against rotation relatively to the cross-head 22 by the engagement with a shallow V-shaped notch 27 in one side of the rocker member, of the complementary end of a spring-pressed plunger 28 mounted in a tubular, cross-head extension 29.

Journalled in the eccentric bore 24 of rocker member 23 is a stud 30 to which is clamped, as by screw 31, the lower end of looper-carrier 10. As will be understood, the axis of stud 30 constitutes the pivot axis about which the looper-carrier is oscillated by link 15 in the reciprocation of the looper 9, that is, toward and from the needle 32 (Fig. 1); and the axis of rock-shaft 17 represents the axis about which the looper-carrier and looper are bodily vibrated laterally with respect to the vertical, reciprocatory movements of the needle. The full-line position of the looper indicated in Fig. 1 represents the limit of its normal movement in a direction away from the needle, or to the right as viewed in that figure.

As will be recognized, the foregoing method of mounting the looper-carrier stud 30 eccentrically in the rocker member 23 provides a ready means for throwing the looper into the dotted line position shown in Fig. 1 in which it is conveniently accessible for threading upon removal of the plate 33, such movement of the looper and its carrier and stud requiring only the rotation of the rocker member 23 from its Fig. 4 or Fig. 1 full-line posi-

tion, into its Fig. 1 dotted line position. The rocker member 23 is limited in its angular movements by the surfaces 23^a and 23^b thereof contacting the vertical wall 22^a of the cross-head 22.

In the illustrated preferred form of the invention such rotation of the rocker member is effected in the manner now to be described.

Secured to the inside of the front wall 34 of the base or housing 3, as by flange 35 and screws 36, is a sleeve 37 in which is slidably and rotatably mounted a control rod 38. To the inner end of control rod 38, within the base 3, is secured a curved crank arm 39 having jaws 40 aligned with arm 25 by a pin 41 projecting from control rod 38 and located in a slot 42 in the sleeve 37. Secured to the other end of the control rod 38, outside the front wall of base 3 and conveniently located beneath the table 2, is a control handle 43 which is counterbored to receive a spring 44 by which the control rod is normally held in its outermost position (Fig. 8, and full-line position of Fig. 2). The inner end of sleeve 37 is provided with a recess 45 forming a lateral extension of slot 42, the recess being bounded by end-wall 46 (Fig. 9).

Thus, in the normal condition and use of the machine, the just-described looper throw-out control means is entirely free of any connection with the looper mechanism itself, including arm 25, with the result that the machine bed can be freely raised for inspection or repair of the under-bed mechanism without requiring the disconnection or disassembly of any part of such control means. However, when it is required to throw the looper to its threading position (the dotted line position of Fig. 1) the control handle 43 is merely thrust inwardly, guided by the movement of pin 41 in slot 42 and causing the jaws 40 to straddle arm 25, and is then rotated from the full line to the dotted line position of the handle as shown in Fig. 3, thereby disengaging plunger 28 from notch 27 and rotating rocker member 23 as above described. During rotation of the control rod 38 the pin 41 rides in the recess 45, the end wall 46 of the recess serving as a limit stop for the pin and for the rotation of the control rod. Reverse rotation of the control rod 38 by handle 43 restores the looper and its carrier to their normal positions, and when the handle is released the spring 44 moves the control rod outwardly to its original position, thereby automatically disengaging the jaws 40 of crank arm 39 from arm 25.

Having thus set forth the nature of the invention, what I claim herein is:

1. In a sewing machine having a bed, a looper-carrier and actuating mechanism therefor located beneath the bed and carried thereby, the looper-carrier being bodily adjustable relatively to the bed, and a base supporting said bed for movement relative to the base, said base enclosing such mechanism, the combination therewith of manually operable carrier-adjusting means mounted on the said base.

2. In a sewing machine having a bed, a looper-carrier and actuating mechanism therefor located beneath the bed and carried thereby, the looper-carrier being bodily adjustable relatively to the bed, and a base supporting said bed for movement relative to the base, said base enclosing such mechanism, the combination therewith of manually operable carrier-adjusting means mounted on the said base, said means being it-

self bodily movable into and out of operative position.

3. In a sewing machine the combination of a looper-carrier, an adjustable support therefor, and manually operable support-adjusting means movable into and out of engagement with the support.

10 4. In a sewing machine the combination of a looper-carrier, an adjustable support therefor, support-adjusting means normally disengaged from the support, and manually operable means for engaging the support-adjusting means with the said support.

15 5. In a sewing machine having a bed and a base, said bed being removably supported on said base, and, supported from the bed within the base, a looper, a looper-carrier, an adjustable support therefor, and actuating means for the looper, the combination therewith of manually operable support-adjusting means mounted on the base.

20 6. In a sewing machine having a bed and a base, said bed being removably supported on said base, and, supported from the bed within the

25 base, a looper, a looper-carrier, an adjustable support therefor, and actuating means for the looper, the combination therewith of manually operable support-adjusting means mounted on the base and movable into and out of engagement with the adjustable support.

30 7. In a sewing machine having a bed and a base, and, supported from the bed within the base, a looper, a looper-carrier, an adjustable support therefor, and actuating means for the looper, the combination therewith of support-adjusting means mounted on the base and normally disengaged from the support, and manually operable means movable to engage the support-adjusting means with the support.

40 8. In a sewing machine having a bed and a base, said bed being removably supported on said base, and, supported from the bed within the base, a looper, a looper-carrier and a support therefor rotatable to adjust the position of the carrier and looper relatively to the bed, the combination therewith of a manually operable support-rotating member mounted on the base.

45 9. In a sewing machine having a bed and a base, and, supported from the bed within the base, a looper, a looper-carrier and a support therefor rotatable to adjust the position of the carrier and looper relatively to the bed, the combination therewith of a rotatable control member mounted on the base with freedom for bodily movement into and out of engagement with said support.

50 10. In a sewing machine having a bed and a base, and, supported from the bed within the base, a looper, a looper-carrier and a support therefor rotatable to adjust the position of the carrier and looper relatively to the bed, the combination therewith of a rotatable control member mounted on the base with freedom for bodily movement into and out of engagement with said support and spring means normally maintaining said control member out of engagement with the support.

55 11. In a mechanism of the character described, the combination with a tubular housing of a member mounted in the housing with freedom for rotary adjustment relatively thereto and having an eccentric bore, a stud mounted in said bore, and a looper-carrier mounted on the stud.

70 12. In a mechanism of the character described,

the combination with a tubular housing of a member mounted in the housing with freedom for rotary adjustment relatively thereto and having an eccentric bore, a stud mounted in said bore, a looper-carrier secured to the stud, means for oscillating the looper-carrier about the axis of the stud, means for transversely oscillating the said housing, and manually operable means for rotating the said number.

13. In a mechanism of the character described, 10

the combination with a tubular housing of a member mounted in the housing with freedom for rotary adjustment relatively thereto and having an eccentric bore, spring means carried by the housing and normally adapted to locate the said member in a fixed position relatively to the housing, a stud mounted in the eccentric bore, and a looper-carrier mounted on the stud.

ANDREW B. CLAYTON.
